UNITED STATES PATENT OFFICE.

JAMES HISATARO TSUTSUMI, OF NEW YORK, N. Y.

DESIGN FOR TEXTILE FABRIC.

SPECIFICATION forming part of Design No. 32,266, dated February 20, 1900.

Application filed December 11, 1899. Serial No. 740,007. Term of patent 3½ years.

To all whom it may concern:

Be it known that I, JAMES HISATARO TSUTSUMI, a citizen of the United States, and a resident of New York city, New York, have invented and produced a new and original Design for Textile Fabric; and I do hereby declare that the drawing accompanying this specification gives and conveys to any one skilled in the art of printing or weaving and manufacturing a clear understanding of the same, of which the following is a description, reference being had to the accompanying drawing, showing the same.

This design is intended to be used for a pattern for neckties.

The fabric shown in the drawing has the dark portion (marked A) representing a border and intersecting lines $b\ c$, $e\ d$, $l\ g$, $f\ h$, $j\ i$,

$k\ h$, and $f\ m$ running through the piece at the angles shown in the drawing. The above-mentioned intersecting lines are a guide for cutting two complete ties within the lines $b\ c$ and $e\ d$, with only the loss of material represented by the triangles $f\ l\ m$ and $k\ h\ i$.

The design is intended to be repeated throughout the length of the fabric.

What I claim is—

The design for textile fabric, substantially as herein shown and described.

Signed at Paterson, in the county of Passaic and State of New Jersey, this 1st day of December, A. D. 1899.

JAMES HISATARO TSUTSUMI.
